UNITED STATES PATENT OFFICE.

JOHN B. RITCHIE, OF MINNEAPOLIS, MINNESOTA, ASSIGNOR OF ONE-HALF TO HERMAN C. HIRSCHY, OF DULUTH, MINNESOTA.

CLOTHES WRINGER.

Application filed August 11, 1924. Serial No. 731,401.

My invention relates to machines for squeezing or extracting water from clothes during the washing process and the object of the invention is to provide a simple, inexpensive apparatus composed of a comparatively few parts and in the manufacture of which all rolls and gears, a constant source of danger to the operator, are entirely eliminated.

10 A further object is to provide a clothes wringing apparatus adapted for operation by fluid pressure and hence particularly useful in localities having water-pressure systems.

15 Other objects of the invention are to provide a fluid operable clothes wringer of cylindrical configuration, having a combined compression and draining element reciprocable therein, and dividing the cylinder 20 into upper and lower chambers, one for receiving clothes to be wrung, and in which the wringing operation takes place, and the other as a compression chamber, having means connected therewith for obtaining 25 compression and release movements of the compression element.

A feature of the invention resides in the specific arrangement and structure of the compression and draining element, and in 30 the connection of a drain tube therewith, which tube communicates with the upper wringing chamber through the compression element, and extends through and outwardly from the compression chamber.

35 Another feature of the invention resides in the combination, of a wash tub, fluid supply pipe, and vertically disposed bracket, separately supported at the rear of and above the tub, with a fluid operable clothes 40 wringer and a flexible fluid supply tube connecting wringer and supply pipe, the wringer body connected with the bracket in a manner adapting it to be brought to two positions relative to the tub, respectively to a lower

45 filling position adjacent the front of the tub, and to an upper locked non-interfering position, whereby the fluid connection between the supply pipe and wringer is maintained when the wringer is at either of its positions, 50 and whereby when the wringer is thrown to an upper position, its lower end is tilted rearwardly in non-interfering position, and the wringer locked.

55 Other objects of the invention will appear from the following description and the ac-

companying drawings and will be pointed out in the annexed claim.

In the drawing there has been disclosed a structure designed to carry out the various objects of the invention but it is to be understood that the invention is not confined to the exact features shown as various changes may be made within the scope of the claim which follows.

In the accompanying drawings forming a part of this specification,

Figure 1 is a view in side elevation of a conventional form of laundry tub showing my invention mounted thereover;

Figure 2 is an enlarged sectional view of the novel clothes wringer showing the preferred type of water valve used in conjunction therewith;

Figure 3 is a plan view of Figure 2 with the cover removed, partially broken away to show the construction of the movable bottom or plunger.

In the selected embodiment of the invention here shown, for purposes of disclosure, there is illustrated a conventional form of laundry tub 4 mounted on the usual base 5. The usual water faucet 6 is shown positioned above the tub and is connected to the water pipe 7 leading to the source of supply.

The novel clothes wringer shown in the accompanying drawings comprises a bucket-like receptacle which is preferably cylindrical in form and is composed of the cylindrical wall 8 and bottom wall 9. The upper end of the receptacle is closed by means of a cover 11 having a notched flange 12 adapted to engage a flange 13 provided on the upper edge of the receptacle as shown in Figures 2 and 3 to secure it thereto. The flange 13 of the receptacle is provided with recesses 14 adapted to receive correspondingly shaped lugs or tongues 15 provided on the inner side of the flange 12 of the cover.

A movable bottom or piston is reciprocably mounted within the receptacle as shown in Figure 2, and divides the cylinder respectively into a wringing and clothes receiving, and a compression chamber. This piston preferably comprises a metallic disk-like head 16 having a series of radial ribs 17 integrally formed on the upper surface thereof. The disk 16 is slightly conical in shape so as to provide a drain for the water towards the center thereof to which a pipe 18 is connected as shown. A perforated disk 19 is prefer-

ably mounted upon the upper face of the disk or head 16 and is suitably secured thereto by such means as the bolts or screws 21. Referring to Figures 2, it will be seen that as a result of the radial ribs on the upper face of the disk 16, spaces or chambers 22 will be formed between the disk 16 and the perforated disk 19. A packing cup or leather 23 is secured to the under side of the head 16 by means of a metallic ring 24 and the screws 25. This leather cup or packing is of ordinary construction and functions to seal the joint between the walls of the receptacle and the movable piston therein. The drain pipe 18 secured to the disk 16 passes through a packing box 26, of ordinary construction, in the bottom wall 9 of the receptacle so that the water being squeezed or extracted from the clothes may be discharged into a suitable receiving means such as the laundry tub shown in Figure 1. This pipe also functions to provide a bearing and support for the piston in its reciprocal movement within the receptacle.

25 The compression and draining element, which is reciprocable in the cylinder and, in this instance, divides the same respectively into an upper clothes receiving and wringing chamber, and a lower compression chamber, 30 comprises a conical disc having a piston fit within the cylinder with its concave side facing towards the wringer chamber, the said conical disc having a perforated flat strainer disc attached to the upper side, forming with the depression of the disc, a drain chamber. As heretofore explained the drain tube is connected to, and movable with the conical disc, and communicates with the drain chamber, and the said tube, as herein shown, extends through the compression chamber and 40 leads outwardly through the bottom of the cylinder, or bucket-like receptacle.

Water is supplied to the under side of the piston through a flexible hose connection 27 having one end connected to the bottom wall 9 of the receptacle by means of a coupling 28 and having its other end connected to a valve 29 which in turn is connected to the usual water faucet 6, as shown in Figure 1, or if desired, it may be connected directly to the water pipe 7. The form of valve here shown is of the three-way type comprising an intake opening 31 and outlet openings 32 and 33. A rotor 34 having a communicating passage 35 is mounted within the casing of the valve and is operable by means of a shaft 36 having a hand wheel 30 or other suitable means mounted thereon whereby the valve may be actuated. This valve forms no part 50 of the present invention and I have therefore thought it unnecessary to show same in detail.

60 In Figure 1, I have shown a form of mounting or supporting means for the clothes wringer comprising a pair of parallel links 37 and 38 which are pivotally connected at one

end to the receptacle by means of pins 39 and at their other ends to a pivotally mounted supporting member 41 which is secured to the wall 42 by means of a bracket 43. Lugs 44 and 45 are preferably provided on the cylindrical wall of the receptacle to provide a supporting means therefor. By means of this novel form of mounting the wringer when inoperative or out of use may be elevated to the position shown in full lines in Figure 1 and 70 it may then be swung to either side against the wall so as to be out of the way of the operator when working over the tub. When in inoperative raised position, the lower pivot pin 39 of the arm 38 will be substantially in 80 alignment with the upper pin 39 of the arm 37 and the lower pivotal connection of the arm 38, thereby retaining the wringer in such position without any other locking means, the weight of the wringer functioning to retain 85 the arms in such inoperative position. When it is desired to use the wringer, a slight outward pull on the receptacle will cause it to assume the position shown in dotted lines where it will be within convenient reach of 90 the operator. It may then be swung over the two tubs and will extend out sufficiently to be within convenient reach of the washing machine 46 indicated in dotted lines in Figure 1. Means may be provided for retaining the 95 wringer in such operative position but I have thought it unnecessary to show same in the drawings.

It will be noted that the wash tub, fluid supply pipe, bracket, and fluid operable clothes wringer are disposed so that the wringer body may be successively brought to two positions, one to a lower filling position adjacent the front of the tub with the drain tube within the tub, and the other at a point rearwardly of and above the tub, while at the same time the connection between the fluid supply pipe and the wringer is maintained. Moreover, it will be noted that means is provided for positively locking the wringer in its upper position, 100 which means comprises the straight link 37, pivoted to the upper part of the bracket and wringer, as shown, and a second shorter link connected to the bottom of the bracket, and with its opposite end curved toward the receptacle and pivotally attached to a rearward extension 45 of the wringer receptacle. 105

It will also be noted that when the wringer is in its uppermost position its lower end is tilted towards the wall or bracket so that the pipe 18 assumes a non-interfering position, even when the wringer is disposed as shown in full lines in Figure 1. Thus it is not necessary that the wringer be pivoted as by member 41, since in its upper locked position, it is disposed in non-interfering relation to the front of the tub.

110 In the operation of this novel clothes wringer, the cover 11 is removed from the receptacle and the clothes or other material to 120

have the water extracted therefrom, is introduced in the receptacle upon the perforated disk 19 which normally is positioned at the bottom of the receptacle. The cover is then placed on the receptacle and locked thereto and the three-way valve opened to permit water pressure to enter the lower portion of the receptacle beneath the piston. As the water flows into the lower portion of the receptacle, the piston will be upwardly moved, carrying with it the clothes until it is brought into contact with the cover. Continued upward movement of the piston, caused by the pressure of the water beneath it, will cause the clothes to be tightly pressed against the cover with the result that the water will be squeezed therefrom and will flow through the perforated disk 19 and into the chambers 22, thence downwardly through the drain pipe 18 to a suitable receiving means. As soon as practically all the water has been extracted from the clothes, the rotor 34 of the valve will be rotated to cut off communication between the source of supply and the receptacle and will be further rotated until the communicating passage 35 thereof will be brought into registration with the outlet ports 32 and 33. The water contained within the receptacle beneath the piston will then flow through the valve and into the tub or other receiving means, thereby allowing the piston to descend to the bottom of the receptacle. The cover may then be removed and the clothes removed from the receptacle.

In the drawings, I have shown the receptacle and cover as being cast or moulded. It is to be understood, however, that the two members may be constructed of sheet metal such as copper, zinc, or aluminum which when suitably reinforced may function equally as well. Other types of valves may also be employed in place of the three-way valve shown and, if desired, the flexible hose connection 27 may be connected directly to the water faucet and the flow of water to the receptacle controlled by the faucet instead of by an auxiliary valve.

I claim as my invention:

A combined pressure and drain element comprising a disk having a concave depression in one face, and having secured upon its opposite face an element of flexible material extended beyond the periphery and adapted to form a sealed closure between the drain element and the side of the vessel within which it operates, a drain pipe secured to and extending through the disk and opening at the center of the concave depression, and a strainer member arranged over the depression and secured to the disk, to form with said depression a drain chamber leading to the pipe, said strainer member having a series of openings therethrough communicating with said drain chamber.

In witness whereof, I have hereunto set my hand this 7th day of August, 1924.

JOHN R. RITCHIE.
